(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing my design;

FIG. 2 is a front view of a second embodiment thereof; and, FIG. 3 is a front view of a third embodiment thereof.

The portions of the graphical user interface that are shaded depict a contrasting appearance. The outermost long and short dashed line in the figures shows a display screen or portion thereof and forms no part of the claimed design. The other broken lines show portions of the graphical user interface that form no part of the claimed design.

1 Claim, 3 Drawing Sheets
